DESIGN FOR A FINGER OPERATED MEMBER FOR CONTROL APPARATUS

William L. Dunn and Richard C. Marholz, Chicago, Ill., assignors to Belmont Radio Corporation, Chicago, Ill., a corporation of Illinois

Application October 31, 1938, Serial No. 80,786

Term of patent 7 years

To all whom it may concern:

Be it known that we, William L. Dunn and Richard C. Marholz, citizens of the United States, residing at Chicago, in the county of Cook and State of Illinois, have invented a new, original, and ornamental Design for a Finger Operated Member for Control Apparatus, of which the following is a specification, reference being had to the accompanying drawing, forming part thereof, in which:

Figure 1 is a side elevation of a finger operated

member for control apparatus showing our new design,

Figure 2 is a front elevation thereof; and

Figure 3 is a top plan view thereof.

We claim:

The ornamental design for a finger operated member for control apparatus, substantially as shown.

WILLIAM L. DUNN.
RICHARD C. MARHOLZ.
